UNITED STATES PATENT OFFICE.

ADOLPH DAMMANN, OF WASHINGTON, DISTRICT OF COLUMBIA.

COLLAR.

No 829,851.

Specification of Letters Patent.

Patented Aug. 28, 1906.

Application filed September 5, 1905. Serial No. 277,014.

To all whom it may concern:

Be it known that I, ADOLPH DAMMANN, a citizen of the United States, residing at Washington, in the District of Columbia, have invented certain new and useful improvements in Collars; and I do declare the following to be a full, clear, and exact description of the invention, such as will enable others skilled in the art to which it appertains to make and use the same.

My invention relates to improvements in collars, and more particularly in the means for attaching them to the neckbands of shirts.

15 The object of the invention is to provide a simple and comparatively inexpensive means upon a collar for quickly and easily attaching it to the back of the neckband of a shirt without the use of a button or other device, 20 which is difficult and inconvenient to apply and liable to cause discomfort to the wearer.

The above and other objects are accomplished by means of the construction illustrated in the accompanying drawings, in 25 which—

Figure 1 is a perspective view of a collar with my improvement applied thereto. Fig. 2 is a sectional view through the collar and the shirt neckband, showing the manner in 30 which the collar is attached to the neckband. Fig. 3 is a perspective view of the stiffening-plate which may be used in the collar-attaching tab, and Fig. 4 is a perspective view of a different style of collar with my 35 improved collar-attaching tab formed therein and provided with a buttonhole, so that the collar may be attached to a neckband by means of a collar-button in the usual manner.

40 In practicing my invention I provide at the back or central portion of the collar a small upwardly-projecting tab, which is adapted to engage the usual buttonhole-flap formed at the back of the neckbands of negligée and other shirts that are closed at the 45 back. This attaching-tab may be either secured to the collar or formed integral therewith, and it may be applied to collars of any style and make and also to either old ones or 50 new ones in the course of their manufacture.

As shown in Figs. 1 and 3 of the drawings, my improved attaching-tab 1 is formed integral with a well-known style of winged collar 2 by cutting the same along two converging and intersecting lines, so as to make 55 the tab of inverted-V shape. The edges of this cut and also of the tab are preferably stitched, as shown at 3, and, if desired, I may insert in the tab 1 before its edges are stitched a stiffening-plate 4. The latter 60 may be formed of metal, celluloid, or other suitable material and, as shown in Fig. 4, is preferably of triangular form; but it will be understood that it and also the tab 1 may be of any other suitable shape. If desired, this 65 stiffening-plate may be omitted and the tab may be formed with a buttonhole 5, as shown in Fig. 4 of the drawings. This buttonhole may be arranged vertically or transversely, as shown, or horizontally or longitudinally, 70 as is more commonly done.

The use and advantages of the invention will be readily understood upon reference to Fig. 2 of the drawings. In applying the collar to the shirt the tab 1 is bent inwardly 75 to a slight extent, so that it may be readily engaged with or slipped beneath the usual buttonhole-flap *a*, formed at the rear of the neckband of a negligée or other shirt *b*. This buttonhole-flap *a* is very generally provided 80 upon negligée and other shirts which are closed at the back, the same being provided so that the collar-button will not come in contact with the back of the neck. The provision of the tab 1 permits the collar to be 85 attached at its rear to the neckband without the use of a collar-button or other device, so that the greatest ease and comfort is given to the wearer, and at the same time the collar 90 may be very quickly and conveniently attached to or detached from the neckband.

Owing to the simplicity of the construction, it will be seen that the tab may be applied to any style of either old or new collars at a comparatively small expense and that by 95 providing the usual buttonhole in the tab the collars may be used in the ordinary manner with collar-buttons or the like.

What I claim is—

The herein-described collar having a V- 100

shaped tab at the rear lower edge thereof and
projecting upwardly therefrom, said tab be-
ing cut from the collar and adapted to hook
into a button-pocket at the rear of the neck-
band of a shirt, and a stiffening-plate stitched
5 into said tab, essentially as described.

In testimony whereof I have hereunto set

my hand in presence of two subscribing wit-
nesses.

ADOLPH DAMMANN
